UNITED STATES PATENT OFFICE.

LEVI L. TOWER, OF CAMBRIDGEPORT, MASSACHUSETTS.

CURRENCY AND STAMP BOX.

Specification forming part of Letters Patent No. **39,184**, dated July 7, 1863.

To all whom it may concern:

Be it known that I, LEVI L. TOWER, of Cambridgeport, in the county of Middlesex and State of Massachusetts, have invented a new and useful or Improved Currency and Stamp Box; and I do hereby declare the same to be fully described in the following specification and represented in the accompanying drawings, making part thereof.

Figure 1 is a top view of my said box as it appears with its cover turned backward. Fig. 2 is a vertical and transverse section of the same. Fig. 3 is a longitudinal and vertical section of one of the retainers or stamp-holders, to be hereinafter described.

In carrying out my invention I construct a box of a rectangular or other desirable form, and make the same of tin or other suitable metal or material, and hinge the cover and the body portions together in the ordinary manner.

In the drawings, A denotes the body portion, and B the cover, of my said box. Within the said body portion I arrange a series of vertical partitions, a a, &c., which divide the said part into the number of apartments I desire to have.

C is the chamber or receptacle for containing bank-notes, while D is that for holding small change, (cents.)

E E' E² E³ denote a series of chambers for postal currency of the different fractional parts of a dollar—viz., fifty cents, twenty-five cents, ten cents, and five cents.

I is the sponge-chamber, which is to have a wet sponge within it, the same being for the purpose of moistening the fingers of a person in order to enable him to more readily withdraw the bills from their respective apartments. The front portion or half of the bottom of each of the chambers E E', &c., I make curved in longitudinal section, as seen in Fig. 2, such curvature o terminating in the same horizontal plane with the top surfaces of the partitions a a, &c., such top surfaces being disposed a short distance—say about three-eighths of an inch—below the surfaces of the sides of the box in order to allow the cover, when its retainers are filled with stamps, to shut down closely upon the body portion.

On the inner surface of the cover B, I dispose one or more series of retainers, b b o' e c

d d, &c., which are a series of curved springs, each of which is fastened at one of its ends to the cover by rivets or by solder, while its other end is free or slightly bears against the cover, as seen in Fig. 2. Each of these holders b b, &c., is intended to retain revenue-stamps of different denominations and characters when placed under it, and some of them may also be used to hold postage-stamps of different value. These stamps should be packed firmly together and placed, respectively, under the spring-holder intended to receive them, and with their faces upward, (when the box may be open,) so that their value and character may be readily seen. Each of these holders should be made of a metal capable of springing and accommodating itself to the number of stamps that may be placed under it, and serve as well to retain a single stamp in its proper place as if a dozen or more were placed under it.

A box constructed in my improved manner, as described and represented, is an article of great utility and advantage to merchants and tradesmen of all classes, as the bills and stamps are not only arranged in a very compact form, but can be easily either put into their receptacles or holders or taken therefrom, as circumstances may render necessary.

I do not claim simply making a box with partitions for dividing it into several compartments for reception of articles of different kinds or characters; neither do I claim a "note-holder," as made of a plate of tin or other metal, and having a series of overlapping flaps arranged upon it, as I am aware that such is not new; neither do I claim the invention as shown and described in the patent granted to George K. Snow on the 21st day of October, A. D. 1862, as my invention differs essentially therefrom; but

I claim—

My combined stamp and currency box, having its parts A and B provided, respectively, with receptacles and retainers, constructed and arranged substantially in manner and for the purposes set forth.

LEVI L. TOWER.
